A. R. WHITEHORN

DIRECT CURRENT RELAY COMPENSATING COIL

Filed March 5, 1921

Witness:
A. Burkhardt

UNITED STATES PATENT OFFICE.

ARTHUR R. WHITEHORN, OF DOWNERS GROVE, ILLINOIS.

DIRECT-CURRENT-RELAY COMPENSATING COIL.

Application filed March 5, 1921. Serial No. 449,795.

To all whom it may concern:

Be it known that I, ARTHUR R. WHITEHORN, a citizen of the United States, residing at Downers Grove, in the county of Du Page and State of Illinois, have invented certain new and useful Improvements in Direct-Current-Relay Compensating Coils, of which the following is a specification.

My invention relates to relay construction and particularly to a direct current relay compensating coil.

In electric relays used in circuits such as signaling, telephoning, telegraphing and the like where small currents flow to the relays, difficulty has been experienced in energizing the armatures of the relay. In railway signals the Railway Signal Association calls for a relay of 4 ohms to attract at .076 and release at .037 amperes and the great difficulty has been to produce a relay to carry out the above requirements without causing a great deal of trouble in the signal system.

An object of my invention is to provide a relay construction for overcoming the objections experienced in the present construction of relays and especially of relays used in track signal systems.

Another object of the invention is to provide a compensating coil for a relay which influences the armature of the relay magnet to a certain extent.

A further object is to improve relay construction for successful commercial use.

Generally speaking I carry out the preferred embodiment of my invention by providing a secondary coil on the same yoke as the primary and influencing the same armature. Preferably a separate source of energy is provided for the secondary coil, the circuit of which is closed by the armature as it is deenergized.

The various novel features of my invention will be apparent from the following specification and drawings and will be particularly pointed out in the appended claims.

In the drawings:

Figure 1 is a schematic drawing of my invention as applied to railway signaling.

Figure 2 is an enlarged front elevation of a magnet constructed in accordance with my invention.

Figure 3 is a side elevation of Figure 2 and;

Figure 4 is a diagrammatic representa-

tion of my invention as applied to a circuit other than a track signaling circuit.

In Figure 1 there is shown a track having a section or block A-B which is the usual block for signaling purposes. In the arrangement shown therein the direction of movement of the train is indicated by the arrow and as shown is from right to left.

At the leaving end of the block, that is at the end A, there is connected a battery C or other source of electrical energy. As is usual practice the battery is connected to the rails and these in turn to a signaling device for maintaining the block signal in proper position in accordance with conditions in the block.

At the B end of the block is a signal of the semaphore type. As is usual practice the target or arm 11 is arranged to be held in vertical position to indicate clear and to be permitted to drop to horizontal position to indicate danger, the arm 11 being maintained in vertical position by means of a relay influenced by the battery C so that the relay will be energized as long as the block is clear. When the relay circuit is opened by design or otherwise, the signal will fall to indicate danger.

Referring to Figures 2 and 3 of the drawings I have therein shown a relay comprising magnets 11 and 12 having pole pieces 13 and 14 influencing the armature 15 hinged to a pivot 18. Below the primary magnets 11 and 12 are secondary magnets 11^a and 12^a respectively, the purpose of which will be explained later. The magnets shown in Figures 2 and 3 are adapted to control a plurality of circuits through upper contacts 16 and lower contacts 17, the armature 15 being pivoted or hinged at 18 and provided with a forwardly extending double contact finger 19 which when the magnet is energized makes electrical connection through the contact pieces 16 and when the magnet is deenergized makes electrical contact through the lower contact points 17.

Referring to Figure 1 of the drawings I have shown a magnet such as that disclosed in Figures 2 and 3 of the drawings having a primary magnet X and secondary magnet X' which act on the armature designated generally by the reference character 20 and which armature may include a plurality of members pivoted at 21 to a suitable support and adapted for simultaneous movement. For supplying a source of energy to the sec-

ondary magnet X' , I provide a second battery 22 from which a single conductor 23 extends to one end of the coil of the magnet X' while a second conductor 24 connects the secondary magnet X' with one of the members 20 on the armature and as long as the magnet X is energized, the armatures 20 will remain in position shown in Figures 1 and 3 of the drawings in which position the magnet X' is de-energized; as soon as the magnet X becomes deenergized the armature drops making contact at point 25 which is the same as lower contact 17 shown in Figure 3 of the drawings. This contact 25 is in electrical connection with battery 22 through the conductor 26 so that when the armature drops a circuit is established from the battery through the secondary magnet X' energizing the same. The amount of current flowing through the magnet X' is not sufficient to attract the armature and thus defeat the purpose of the relay. The current is just sufficient to influence the armature to such an extent as to keep the same in what may be termed a floating condition or in a state of equilibrium tending to overcome the attraction of gravity on the armature so that when the primary magnet X is energized the armatures will be attracted immediately by reason of the fact that the primary magnet does not have to overcome the attraction of gravity, and of the air gap between the pole pieces and the armature. The secondary magnet may be said to kick the armature and aid it in its upward movement. As soon as the armature breaks connection with the contact 25 the secondary magnet of course becomes deenergized.

In Figure 1 I have also shown an intermediate relay comprising a primary magnet Y and a secondary magnet Y' constructed and functioning as described with respect to the magnet X and X' . However, the circuits controlled by the armature 27 of the magnet Y are slightly different from those controlled by the armature 20 magnet X . When the block A-B is clear the magnet Y of the intermediate relay is energized attracting armature 27, current flows from battery 31 through conductors 32, 33, primary magnet X back through conductor 28, contact 16, resistance 30 to the battery 31. This circuit controls the energization of the primary magnet X which operates the signal in the next preceding block that is at the "B" end of the block A-B. The resistance 30 limits the amount of flow of the current when the magnet Y is energized to take care of short circuits due to trains being on the track, track leakage and the like.

As soon as the magnet Y is deenergized

by the train leaving the left section of the block A-B the armature 27 falls making contact with the lower contact point 17. Thereupon, the battery 31 sends a current through conductor 34, secondary magnet Y' , conductor 35, lower contact 17, conductor 36 to conductor 32, back to the battery. This causes energization of the secondary magnet Y' only to the extent that the armature may be neutral or maintained in a state of equilibrium so that when the primary magnet Y is energized the armature 27 will be attracted immediately. It will be noted that the circuit to the primary magnet X is controlled through the armature of the magnet Y . This construction is used in certain types of signal systems.

While I have shown my invention as used in connection with a signal system it is not limited to such use. In Figure 4 I have shown a wiring diagram including a battery or other source of electric energy 37, included in a circuit in which there is a primary magnet 38 and a secondary magnet 39, both influencing armature 40. Included in the circuit between the battery 37 and the primary magnet 38 is a switch 41 which may open and close the circuit from the battery to the magnet. As long as this switch remains closed the magnet is energized and the armature attracted so that any circuit in which is included upper contact 42 would be closed. As soon as the switch 41 is opened the armature 40 drops breaking the circuit in which is included the upper contact 42. When the armature 40 drops it makes contact with the point 43 in circuit with the battery 44 in the conductor 45 which includes the secondary magnet 39 so that here too the secondary magnet becomes energized as soon as the armature is deenergized, the secondary magnet in this instance performing the same function as that in the illustration heretofore described. The diagram at the right hand of Figure 4 illustrates the circuit established when the switch 41 is opened.

While I have described more or less precisely the details of construction of my invention, I do not wish to be understood as limiting myself thereto, as I contemplate changes in form and the proportion of parts and substitution of equivalents as circumstances may suggest or render expedient without departing from the spirit of my invention.

I claim:

1. A relay construction including a magnet and an armature influenced thereby, said armature adapted to close selected circuits under certain conditions, a second magnet adapted also to influence said armature and an energizing circuit for said second magnet controlled by said armature and adapted to be closed thereby while said first magnet is deenergized.

2. A relay, including a magnet and an armature, a plurality of circuits controllable by position of said armature, one circuit adapted to be closed when said magnet is energized and another circuit adapted to be closed when said magnet is de-energized, a second magnet established to influence said armature and included in the circuit closed by said armature when said first magnet is de-energized, said latter circuit including a separate source of energy from the first magnet.

3. A relay including a single armature and two magnets, each magnet having a different source of energy supply, and one of said magnets having a circuit opened or closed by said armature under the influence of said other magnet.

4. An interdependent relay construction including an actuating relay set and a con-

trol relay for said set, each of said relays including a single armature and two magnets therefor, said actuating relay set being caused to function after said controlling relay has become energized.

5. A relay including a primary and a secondary magnet mounted on one yoke, an armature adapted to control selected circuits under certain conditions responsive to said magnets, an energizing circuit for the secondary magnet and an energizing circuit for the primary magnet, said secondary magnet circuit adapted to be closed by said armature while said primary magnet remains open for compensating gravity whereby said armature may respond immediately whenever said primary circuit is closed.

Signed at Downers Grove, Illinois, this 19th day of February, 1921.

ARTHUR R. WHITEHORN.
